TOOLHOLDING ATTACHMENT FOR LATHES

John A. Honegger, Bloomfield, N. J., assignor to
Kidde Manufacturing Co., Inc., Bloomfield,
N. J., a corporation of Delaware

Application March 26, 1942, Serial No. 436,297

3 Claims. (Cl. 29—48)

The present invention relates to lathes, and more particularly to an attachment for mounting a plurality of tools.

The present invention aims to provide a toolholding attachment which is particularly adapted to be used in connection with metalworking lathes and the like. The attachment is adapted to be mounted on the tailstock of a single purpose lathe to thereby convert the lathe into a "multipurpose" or turret lathe. The 10 attachment is also adapted to be mounted on the tool turret of a turret lathe to increase the number of operations which may be performed by the lathe.

An object of the present invention is to provide an improved, simple and inexpensive toolholding attachment which serves as a tool turret and increases the utility of lathes.

Another object is to provide an attachment for mounting a group of tools which are adapted to be selectively moved into their work engaging position in a convenient manner.

Another object is to provide a toolholding attachment having a rotatable turret-like member adapted to be readily locked in a predetermined desired position and unlocked and moved to another position.

Another object is to provide a toolholding attachment comprising a minimum number of parts which may be economically manufactured and can be rapidly assembled in a minimum number of operations.

Another object is to provide a toolholding attachment adapted to withstand rough usage without getting out of adjustment or repair.

A further object consists in the combination and arrangement of the parts of the attachment, whereby the foregoing objects may be accomplished.

Other and further objects of the invention will be obvious upon an understanding of the illustrative embodiment about to be described, or will be indicated in the appended claims, and various advantages not referred to herein will occur to one skilled in the art upon employment of the invention in practice.

A preferred embodiment of the invention has been chosen for purposes of illustration and description and is shown in the accompanying drawing, forming a part of the specification, wherein:

Figure 1 is a top plan view of the tailstock of a lathe having an attachment, illustrating an embodiment of the invention, mounted thereon.

Figure 2 is an enlarged sectional view taken substantially along the line 2—2 on Figure 1.

Figure 3 is an enlarged bottom plan view, with certain parts of the attachment broken away for clearness.

Referring to the drawing, and more particularly to Figure 1 thereof, there is shown a toolholding attachment 10, in accordance with the invention, mounted on the tailstock 11 of a lathe. While the attachment is shown as used in connection with a tailstock, for illustrative purpose, it will be understood that the attachment may also be mounted at one of the tool stations in a tool turret of a turret type lathe, as will be described hereinafter.

The attachment, as shown in Figures 2 and 3, comprises a body member 12 having a lower clamping flange or cradle plate 14; an upper clamping flange or plate 15, parallel to and spaced from the lower flange 14; and a circular disc-like turret member 16 rotatably mounted in the space between the flanges.

The body member 12 has a vertical wall portion 17 at one end thereof which is provided with an 25 arcuate, inwardly facing surface 19 for receiving the rotatable turret member 16. The wall portion 17 is further provided with an aperture 20 for receiving one end of a tapered shank 21 adapted to fit into the tool clamp of a tailstock 20 or a tool turret. The shank 21 preferably is secured to the body member by a cross pin 22, or the like, which enables the shank to be readily detached and replaced by shanks having other diameters or tapers, whereby the attachment 35 can be used in connection with lathes varying in size over a wide range.

The lower flange 14 of the body member is adapted to support the lower face of the turret member 16 and is provided with an aperture 24 40 adapted to receive a bolt 25, or the like, for rotatably mounting the turret member. The lower flange also carries an indexing device 26 (Figure 3) which will be described in detail hereinafter.

The upper flange or plate 15 may be substantially 45 triangular in shape (Figure 1) and is attached to the body member 12 by a pair of machine screws 27 or the like, extending through apertures 29 in the plate 15 and threaded into the upper end of the wall portion 17. At the 50 apex of the plate 15, an aperture 30 is provided for receiving the bolt 25. Preferably, the upper plate 15 or the upper end of the wall portion 17 is provided with a pair of thrust pins 31 and, respectively, the upper end of the wall portion 17 55 or the plate is provided with apertures 32 for

receiving the pins 31. These pins when inserted into their apertures serve to maintain the aperture 30 of the upper plate in alignment with the aperture 24 of the lower plate, and prevent side-wise shifting of the plate 15 when the screws 27 are slightly unscrewed to facilitate the clamping action of the plates 14 and 15.

The turret member 16 preferably is in the form of a circular disc of suitable thickness to be provided with a plurality or series of circumferentially spaced radially extending apertures 34 for receiving the shanks of a group of tools A, B, C and D (Figure 1). The shanks of the tools are adapted to be secured in the apertures 34 by set screws 35, or the like, threaded into apertures 36 extending downwardly from the upper face of the turret member. When the screws 35 are in tool securing position, they are fully confined in the apertures and do not extend above the upper face, whereby the screws will not interfere with the rotation of the turret member between the upper and lower plates.

The turret member 16 is provided with a centrally located aperture 37 for the bolt 25 which extends through the upper and lower plates and serves to rotatably mount the turret member. The head end of the bolt carries a lock washer 38 which engages the underside of the lower flange to prevent rotation of the bolt 25 and the free end of the bolt projects upwardly out of the upper flange 15. The free end of the bolt has threads 39 for screwing on the threaded hub 40 of a clamping lever 41 adapted to bear against the top side of the upper flange to urge the flanges 14 and 15 into clamping relation with the turret member 16 and thereby prevent rotative movement of the turret member.

The indexing device 26 is illustrated more particularly in Figures 2 and 3. This device comprises a pin 42 extending through a vertical aperture 44 in the lower flange or cradle plate 14. The center of the aperture is in a vertical plane extending through the longitudinal axis of the shank 21 and is diametrically opposite the point at which the tools are placed into working position. In order to selectively place each of the tools into working position, recesses or apertures 45 are provided in the lower face of the turret member, each recess being diametrically opposite the tool it indexes and being spaced from the center of the turret member the same distance as the pin 42 so that the pin is adapted to extend therein to effect indexing.

The pin 42 preferably is slidably disposed in a boss 46 which is laterally slotted at 47 for receiving a lever or arm 49 for sliding the pin into and out of index recess engaging position. The lever 49 is disposed in a slot 50 at the lower end of the pin and is pivotally connected thereto by a cross pin 51 passing through the slotted end of the pin and through an aperture 52 in the lever.

One end of the lever 49 is pivotally mounted at the underside of the lower flange by a shaft or rod 54 supported on bearing members 55. A spring 56, or other suitable resilient means, adjacent the bearing members, serves to urge the lever upwardly toward the underside of the lower flange and thereby urge the index pin 42 into index recess engaging position.

In use, the toolholding attachment is adapted to be secured to the tailstock of a single purpose lathe, as illustrated in Figure 1 and the four tools A, B, C and D are secured to the turret member 16. These tools may be adapted to perform different operations on the work piece in selected se-

quence. For example, A may be a center drill, B may be a boring or drilling tool, C may be a spot-facing tool, and D may be a tapping or threading tool. The tools may be placed successively into work engaging position in the selected sequence, by loosening the clamping lever 41 and pressing the free end of the index pin operating lever downwardly to move the pin 42 out of indexing position. The turret member may then be rotated into its desired position and secured in place by screwing down the clamping lever. In the foregoing manner a single purpose lathe is converted into a lathe adapted to perform a sequence of operations.

The attachment may also be used in connection with a turret lathe having a tool turret which usually is provided with six stations or tool supporting clamps. Such lathe is limited to perform six operations, but this number can be increased to nine or more by securing one or more attachments, in accordance with the invention, in the tool clamps of the turret. By using the present attachment, complex articles can be made entirely on one machine and the series of operations can be performed without interruption.

From the foregoing description it will be seen that the present invention provides an improved toolholding attachment for increasing the utility of lathes. The attachment is simple in construction and may be economically manufactured. The attachment is rugged in construction and can readily withstand any rough usage to which it may be subjected.

While my invention resides in certain principles of construction and operation, which have been illustrated and described in connection with the accompanying drawing, it will be apparent to those skilled in the art that the invention may be embodied in other forms of construction without departing in any manner from the spirit and scope of the invention, and I therefore do not wish to be strictly limited to the disclosure, but rather to the scope of the appended claims.

I claim:

1. A lathe attachment comprising a body member having a clamping flange and having a wall portion provided with an arcuate surface; a clamping flange mounted on said wall portion; means for removably securing said second clamping flange on said wall portion; a disc-shaped turret member intermediate said flanges having an arcuate peripheral surface disposed adjacent the arcuate surface of said wall portion, tool retaining means at its periphery substantially diametrically opposite its arcuate surface, and having a lower face seated on the flange of said body member and provided with a series of index recesses; a pin extending through the flange of said body member adapted to project into said recesses; means mounted on said body member for retracting said pin; said flanges and said turret member each having an aperture therein; a bolt member extending through said apertures; clamping means on said bolt member for causing said flanges to clamp said turret member to prevent rotation thereof; and a shank removably secured to the wall portion of said body member.

2. A lathe attachment comprising a body member having an integral clamping flange and a wall portion provided with an arcuate surface; a second clamping flange mounted on said wall portion; means for removably clamping said second flange to said wall portion; a disc shaped turret member intermediate said flanges having an arcuate peripheral surface disposed adjacent the

arcuate surface of said wall portion; said turret member having a series of circumferentially spaced radially extending apertures for receiving shanks of a series of tools and having a series of index recesses substantially diametrically opposite said apertures; screw members associated with each of said apertures and below the upper surface of said turret member for securing the said tool shanks in said apertures; said clamping flange of the body member having an aperture extending therethrough; a pin normally entirely within said aperture and adapted to engage the recesses in said turret member; and a lever pivotally mounted on said body member and pivotally secured to said pin for retracting said pin from said recess.

3. A lathe attachment comprising a body member having an integral clamping flange and a wall portion provided with an arcuate surface; a second clamping flange mounted on said wall portion; means for removably clamping said second flange to said wall portion; a disc shaped turret member intermediate said flanges having an arcuate peripheral surface disposed adjacent the

arcuate surface of said wall portion; said turret member having a series of circumferentially spaced radially extending apertures for receiving shanks of a series of tools and having a series of index recesses substantially diametrically opposite said apertures; screw members associated with each of said apertures and below the upper surface of said turret member for securing the said tool shanks in said apertures; said clamping flange of the body member having an aperture extending therethrough; a pin normally entirely within said aperture and adapted to engage the recesses in said turret member; a lever pivotally mounted on said body member and pivotally secured to said pin for retracting said pin from said recess; a bolt extending through said turret member and said flanges having a head at one end engaging one of said flanges and being screw threaded at its other end; and a clamping member on the screw threaded end of said bolt for causing said flanges to clamp said turret member to prevent rotation thereof.

JOHN A. HONEGGER.
